UNITED STATES PATENT OFFICE.

JOHANN STUMPF, OF CHARLOTTENBURG, GERMANY, ASSIGNOR TO GENERAL ELECTRIC COMPANY, A CORPORATION OF NEW YORK.

STEAM-TURBINE.

SPECIFICATION forming part of Letters Patent No. 790,405, dated May 23, 1905.

Application filed February 24, 1903. Renewed September 22, 1904. Serial No. 225,458.

To all whom it may concern:

Be it known that I, JOHANN STUMPF, a subject of the King of Prussia, German Emperor, and a resident of 28 Rankestrasse, Charlottenburg, near Berlin, Kingdom of Prussia, German Empire, have invented certain new and useful Improvements in Steam or Gas Turbines, of which the following is an exact specification.

10 My invention relates to improvements in steam or gas turbines, and more especially to means for varying the speed of such turbines.

In using steam-turbines for actuating screw-propellers, pumps, and the like apparatus, in which it is sometimes necessary to alter or change the number of revolutions for unit of time, great disadvantages always result, owing to the fact that the angle of delivery of the steam—that is, the angle which the inlet-nozzles make with the turbine-wheel—is always adjusted to a certain number of revolutions. If the turbine runs at any other speed, small shocks arise in the turbine in consequence of the angle of inclination of the nozzles not being suitable for this different number of revolutions. In all turbines the streaming velocity of the steam, the velocity at the circumference of the turbine-wheel, and the angle of inclination of the nozzles, as well as of the buckets or shovels of the turbine-wheel, are dependent upon one another. This dependence may easily be seen from the diagram of velocities.

The losses mentioned above are avoided according to the present invention by arranging several rows of nozzles, which nozzles may have the same form, but the angle of inclination thereof is different.

In order to make my invention more clear, I refer to the accompanying drawings, in which—

Figure 1 is a vertical section of a turbine constructed according to my invention. Figs. 2, 3, and 4 are diagrams.

In the drawings, a is a turbine-wheel provided with buckets or vanes c . The turbine-wheel a is fixed upon a shaft g , which can be moved sidewise by means of a lever h , journaled at i , or by means of any other suitable device.

e' and e^2 are admission-channels situated around the turbine-wheel and provided with nozzles f' and f^2 , through which the steam flows in the well-known manner upon the turbine-wheel. In the drawings the turbine-wheel is shown in the position in which the steam flows through the channel e' and the nozzles f' into the buckets c . If the steam admitted to the channel e' is shut off, the turbine-wheel moves to the left-hand side, and steam is admitted to the channel e^2 , the steam will flow through the nozzles f^2 , having a different angle of inclination from the nozzles f' , into the buckets c of the turbine-wheel.

In Figs. 2 to 4 of the accompanying drawings turbine-wheel vanes of the well-known Laval type are shown. The nozzles are inclined at different angles. The streaming velocity of the admission-steam is in all three cases shown represented by the letter w and equals nine hundred and eighty meters. In Fig. 2 the turbine is supposed to run at three thousand revolutions per minute, in Fig. 3 at two thousand two hundred revolutions per minute, and in Fig. 4 at fifteen hundred revolutions. The velocity (represented by v' , v^2 , and v^3) at the circumference of the turbine-wheel is consequently three hundred and fifty meters, two hundred and sixty meters, and one hundred and seventy-five meters per second in Figs. 2, 3, and 4, respectively. The relative streaming velocities of the admission-steam of the vanes will consequently be found to be $c'=675$ meters, $c^2=740$ meters, and $c^3=810$ meters. The angle of inclination of the admission-nozzles is in Fig. 2 equal to twenty-four degrees, in Fig. 3 equal to twenty-eight degrees, and in Fig. 4 equal to thirty degrees. In these examples it is assumed that the bucket-wheels are of the same diameter.

Having thus fully described the nature of this invention, what I desire to secure by Letters Patent of the United States is—

1. In a turbine, the combination with a turbine-wheel provided with one row of shovels, of several rows of nozzles situated around the turbine-wheel, and means for moving the turbine-wheel in the direction of the axis of the same, so as to allow the same to be impinged

upon by each row of nozzles, substantially as described and for the purpose set forth.

2. In an elastic-fluid turbine, the combination of a set of wheel-buckets, sets of nozzles, 5 and means for moving the sets of buckets and nozzles with respect to each other so as to bring the set of buckets in position to receive fluid from the nozzle or nozzles of any set.

3. In an elastic-fluid turbine, the combination 10 of wheel-buckets, nozzles having different formations, a support therefor, and means for shifting the support and wheel-buckets relatively to each other to aline the buckets with any given nozzle.

15 4. In an elastic-fluid turbine, the combination of independent supply-chambers, nozzles arranged in sets which receive motive fluid from the chambers, wheel-buckets, and means for shifting the wheel-buckets and nozzles 20 relatively to each other to aline one set of nozzles or another with the buckets.

5. In an elastic-fluid turbine, the combina-

tion of a bucket-wheel, a series of independent chambers encircling the wheel, separate sets of nozzles having different angles of delivery receiving motive fluid from the chambers, and means for moving the nozzles and wheel relative to each other in an axial direction to aline any given set of nozzles with the wheel.

25 6. In an elastic-fluid turbine, the combination of a wheel having buckets all of which are active when the turbine is in service, separate sets of nozzles, a support therefor, and a means for shifting the buckets and nozzles 30 relatively to each other to aline the buckets with any given set of nozzles.

In testimony whereof I have signed my name to this specification in the presence of two subscribing witnesses.

JOHANN STUMPF.
